ATTACHMENT FOR SEWING MACHINES

Filed March 7, 1929

王五

UNITED STATES PATENT OFFICE

WILLIAM C. HAKE, OF ST. LOUIS, MISSOURI

ATTACHMENT FOR SEWING MACHINES

Application filed March 7, 1929. Serial No. 345,018.

This invention relates to an attachment for sewing machines particularly adapted for feeding tape to form a French binding for shoes.

5 An object of the invention is to provide an attachment whereby tape from a continuous row may be fed to the stitching point for attachment to the edge of shoe uppers, which attachment is adapted to wipe out the upper 10 edge of the tape and to prevent it from coming in contact with the needle in the stitching operation.

Another object of the invention is to provide an attachment of the kind described having 15 an adjustable device for holding the top margin of the tape above the stitching point, said attachment being adapted for adjustment to tape of different widths.

Additional advantages of the construction 20 will be apparent from the following detailed description taken in connection with the accompanying drawing, in which

Fig. 1 is a front elevation of the attachment and associated parts.

25 Fig. 2 is a side view of the same elements. Fig. 3 is a transverse section showing the parts in detail.

Fig. 4 is a front face view of the roller with the adjustable device associated therewith.

30 Fig. 5 is a detailed view of the mounting for the adjustable device.

Fig. 6 illustrates a portion of a shoe upper with a tape attached to the margin thereof.

35 Fig. 7 is a sectional view showing the means for adjusting the device for tape of different widths.

In the embodiment of the invention illustrated in the drawing the attachment is shown in association with a sewing machine having

40 a top arm 1 illustrated fragmentarily in Figs. 1 and 2. A needle bar 2 carrying a needle 3 is mounted in the arm 1 for vertical reciprocation. The arm 1 has connected therewith a bracket 4. An arm 5 is removably attached

45 to the bracket 4, said arm 5 curving inwardly and downwardly. The arm 5 has connected to its lower end a stud bolt 6 which constitutes a shaft for a presser roller 7. The front face of the presser roller is dished as clearly shown

50 in Fig. 3 of the drawing, and the periphery

of the roller comprises a serrated face 8. The roller 7 is mounted upon its shaft in a forwardly inclined position as best shown in Fig. 3 of the drawing.

The mechanism for feeding the tape includes an arm 9 removably attached to the bracket 4, said arm extending rearwardly and downwardly and supporting a tape guide member that includes a plate 10 having an eye 11 attached to its rear edge, said plate extending at the back of the attachment and communicating with a tape feed tube 12 that extends across the front face of the presser roller. The tape feed tube comprises a front and rear wall joined together so that said walls lie close together and so that the vertical dimension is sufficient to accommodate, at its inlet end, tape of varying widths fed to the stitching point. The forward throat of the tube is deflected slightly outwardly at 13 for turning the lower marginal edge of the tape to meet the surface of the shoe upper in a plane parallel therewith at the stitching point, in cooperation with the beveled wall of the presser roller. The forward throat of the tube 12 has a single wall extension 14, the upper marginal edge of which is slightly notched at 15, as shown in Fig. 2 of the drawing. The purpose of the extension 14 is to hold the upper marginal edge of the tape out of the path of the needle.

In order to accommodate the device for feeding different widths of tape, an adjustable member is provided to engage the upper marginal edge of the tape as it leaves the throat of the tape feed tube. This member comprises a stem 16 mounted in a bracket 17 attached to the front face of the upper portion of the arm 9. An expansion spring 18 is mounted on the stem 16 between the lower face of the bracket 17 and a flange 19 on the stem. An adjusting nut 20 is mounted over a threaded end of the stem for raising the stem in the bracket 17 against the tendency of the spring 18 to depress the stem. Thus, the stem may be raised and lowered by the operator. When the proper adjustment of the stem has been attained, it may be set in position by a set screw 21 threaded into the face of the bracket 17 and against the stem.

The bracket 17 is connected with the arm 9 by a stud 22 that extends through an elongated opening 23 in the arm 9. A nut 24 threads over the extremity of the stud 22 so that a slight longitudinal adjustment of the bracket 17 may be effected. Below the flange 19 is an extension of the stem constituting an angular arm 25, the lower portion of which extends rearwardly and downwardly to a point below the upper edge of the tape feed tube. The extremity 26 of the arm 25 is bifurcated and is inclined inwardly to an apex, clearly shown in Fig. 4 of the drawing. The space between the arms forming the bifurcated extremity constitutes a channel through which the upper marginal edge of the tape passes as it is fed through the device. By varying the tension of the spring 18, the elevation of the seat of the channel formed in the bifurcated extremity 26 may be accurately adjusted. Therefore, when the tape of varying widths is used, the pressure on the upper marginal edge thereof may be accurately adjusted so that the lower marginal edge of the tape is forced into the lower channel in the tape feeding tube, toward the marginal edge thereof, along an accurately positioned line in respect of the needle which passes through the tape as it leaves the deflected portion 13 of the throat of the tube. The extremity 26 also serves to hold the upper marginal edge of the tape in a vertical position and to prevent it from curling inwardly and therefore out of the path of the needle 3. The device is so constructed as to accurately lay the tape at the stitching point, regardless of the nature of the contour of the shoe upper to which the tape is to be attached. I am aware that the invention may be varied in numerous particulars without departing from the nature and principle thereof.

I do not limit myself unessentially, but what I claim and desire to secure by Letters Patent is:—

1. In a sewing machine, the combination with stitching mechanism and feeding mechanism, said feeding mechanism including a presser roller having a concave face; of an attachment adapted to feed tape to the stitching point comprising the tape feed tube arranged vertically adjacent to the concave face of said roller, and having an outwardly turned portion near its lower marginal edge, whereby the tape is fed against the concave face of the presser roller and the outer edge thereof is presented to the stitching point in substantially a horizontal plane; and an adjustable member having a vertical channel therein for engaging the upper marginal edge of the tape.

2. In a sewing machine, the combination with stitching mechanism and feeding mechanism, said feeding mechanism including a presser roller having a concave face; of an

attachment adapted to feed tape to the stitching point comprising the tape feed tube arranged vertically adjacent to the concave face of said roller, and having an outwardly turned portion near its lower marginal edge, whereby the tape is fed against the concave face of the presser roller and the outer edge thereof is presented to the stitching point in substantially a horizontal plane; and an adjustable member comprising a stem having an angular extremity adapted to engage the upper marginal edge of the tape and to hold it in substantially vertical position with a predetermined downward pressure thereon.

3. In a sewing machine, the combination with stitching mechanism and feeding mechanism, said feeding mechanism including a presser roller having a concave face; of an attachment adapted to feed tape to the stitching point comprising the tape feed tube arranged vertically adjacent to the concave face of said roller, and having an outwardly turned portion near its lower marginal edge, whereby the tape is fed against the concave face of the presser roller and the outer edge thereof is presented to the stitching point in substantially a horizontal plane; and an adjustable member comprising a vertically movable stem; a spring normally actuating said stem downwardly, an adjusting nut operating in opposition to said spring, an angular extension for said stem having a channel formed in its lower end, said channel adapted to provide a guideway for the upper marginal edge of the tape and to hold the upper marginal edge of the tape in a vertical position and to force the body of the tape against the lower wall of the tape feed tube.

4. In a sewing machine, the combination with stitching mechanism and feeding mechanism, said feeding mechanism including a presser roller having a concave face; of an attachment adapted to feed tape to the stitching point comprising the tape feed tube arranged vertically adjacent to the concave face of said roller, and having an outwardly turned portion near its lower marginal edge, whereby the tape is fed against the concave face of the presser roller and the outer edge thereof is presented to the stitching point in substantially a horizontal plane; and an adjustable member comprising a vertically movable stem; a spring normally actuating said stem downwardly, an adjusting nut operating in opposition to said spring, an angular extension for said stem having a channel formed in its lower end, said channel adapted to provide a guideway for the upper marginal edge of the tape and to hold the upper marginal edge of the tape in a vertical position and to force the body of the tape against the lower wall of the tape feed tube, and a set screw adapted to lock the stem in its selected adjusted positions.

5. In a sewing machine, the combination with stitching mechanism and feeding mechanism, said feeding mechanism including a presser roller having a concave face; of an attachment adapted to feed tape to the stitching point comprising the tape feed tube arranged vertically adjacent to the concave face of said roller, and having an outwardly turned portion near its lower marginal edge, 10 and a single wall extension from the upper edge of the throat thereof, whereby the tape is fed against the concave face of the presser roller and the outer edge thereof is presented to the stitching point in substantially a horizontal plane; and an adjustable member having a vertical channel therein for engaging the upper marginal edge of the tape.
